UNITED STATES PATENT OFFICE.

WILLIAM J. BAUER, OF LINCOLN, ILLINOIS.

BOILER-CLEANER.

1,331,452.

Specification of Letters Patent. Patented Feb. 17, 1920.

Application filed May 12, 1916. Serial No. 96,984.

To all whom it may concern:

Be it known that I, WILLIAM J. BAUER, a citizen of the United States, and a resident of Lincoln, in the county of Logan and State of Illinois, have invented certain new and useful Improvements in Boiler-Cleaners, of which the following is a specification.

My invention relates to boiler cleaners particularly useful for removing scum, foam, or other impurities from the surface of the water within a boiler.

Among the important objects of the invention are to produce a more simple and efficient structure which can be readily inserted in different classes and makes of boilers; to provide a structure involving a counter-balanced float intake frame which can quickly follow the varying levels of the water in a boiler to keep the inlet openings at the water surface in order to collect and remove scum or other impurities; to provide improved non-collapsible and inflatable float members for the float frame; and in general to improve on the construction and arrangement in apparatus of the class described.

An apparatus embodying the features of my invention is illustrated on the accompanying drawing. In this drawing—

Figure 1 is a plan view of such apparatus mounted on a boiler pipe.

Fig. 2 is a side elevational view of the parts shown in Fig. 1,

Fig. 3 is a sectional view on plane 3—3, Fig. 1, a boiler shell being shown in cross-section,

Fig. 4 is an enlarged sectional view on plane 4—4, Fig. 2,

Fig. 5 is an enlarged sectional view through one of the oscillating joints, and

Fig. 6 is a sectional view on plane 6—6, Fig. 5.

The apparatus shown comprises longitudinal piping 10 to which cross piping 11 and 12 is connected at the ends by T-fittings 13 and 14. The transverse longitudinal piping is interconnected and a valve fitting 15 controls the outlet therefrom, the valve lever 16 being connected by rod 17 to the exterior of the boiler in which the apparatus is installed. In the drawings, particularly Fig. 3, the apparatus is shown applied in a locomotive boiler 18 and is mounted on the dry pipe 19 usually found in such

boilers. From the cross-piping 11 and 12 pipe lengths 20 and 21 depend from T-fittings 22 and 23 inserted in the piping, and these pipe lengths terminating in caps 24 having loops 25 for receiving the straps 26 and 27 connected together at their lower ends by a bolt 28. When the apparatus is installed the longitudinal piping 10 rests on top of the boiler dry pipe with the pipe lengths 20 straddling the pipe, the straps extending underneath the pipe so that the entire structure is clamped to the dry pipe.

Extending downwardly from the ends of the cross pipings 11 and 12 are the pipe legs 29 and 30 to whose lower ends pipe links 31 and 32 are connected by couplings 33 and 34, the outer ends of each set of links 31 and 32 being connected by couplings 35 and 36 with the respective ends of a scum intake pipe 37, these intake pipes having the lateral inlet openings 38. On each intake pipe 37 float members 39 are supported. These float members rest in the water and assist in keeping the inlet openings 38 at the water surface in order that scum, foam or other impurities may enter pipes 37 to be driven through links 31 and 32, the cross piping 11 and 12 and the longitudinal piping 10, and through the outlet pipe 40 which is controlled by the valve 15, the pipe 40 leading to the exterior of the boiler, it being understood that the steam pressure in the boiler forces the scum through the apparatus when the valve 15 is open.

In Figs. 5 and 6 the detailed construction of the oscillatory pipe couplings is shown, the couplings connecting the links with the intake pipes 38 and the supporting pipe frame being of the same construction. As shown, each coupling comprises the hollow cylindrical heads 41 and 42 whose inner walls 43 and 44 have axial openings through which a tube 45 extends, the tube being threaded at its ends for the reception of nuts 46 and 47. Sleeves 48 and 49 extend from the heads 41 and 42 respectively in which sleeves are secured the ends of the pipes which the coupling is intended to connect together. By means of the tube and nut arrangement the coupling heads can be secured together but free to readily rotate relatively to permit the floats to follow the varying levels of the water. In order that the tube and nuts in each coupling may be readily inserted or inspected the outer walls 100

50 and 51 of the respective heads have screw threaded engagement, tongues 52 being provided thereon for receiving a wrench.

In order to assist the floated pipes 37 to readily follow the water level, counter-balance weights 53 are provided on arms 54 extending rearwardly from lugs 55 which connect with the links 31 and 32. The weights 53 are adjustable on the supporting rods 54 in order that the weights can be made to accurately coöperate with the buoyancy of the floats to at all times keep the inlets 38 in position to receive scum or other impurities.

The float members 39 are also preferably revolvably adjustable with reference to their supporting pipes 37 in order that further adjustment can be made to assure keeping of the scum inlets at the water surface. As shown, each unit 39 is of substantially cylindrical shape and is supported in straps or rings 56 at the ends of legs 57 extending from the split clamping sleeve 58 which receives the supporting pipe 37, the ends of the clamp being connected by a screw 59 and a set screw 60 being provided in the body of the clamp to engage with the supporting pipe. To adjust the float members the set screw 60 and the clamping screws 59 are first loosened and adjustment made, and then the screws are tightened to secure the units rigidly in adjusted position with reference to the pipes. Preferably the floats are distributed on both sides of the intake pipes in order to more efficiently balance the floating structure and to reduce the friction at the oscillating joints. As shown best in Fig. 1, the floats at the end of each pipe 37 are at the outside and the two intermediate floats are at the inside of the pipes. In Figs. 1 and 2 the links 31 and 32 are almost at right angles with the vertical pipes 29 and 30, the pipes 37 being down a considerable distance to follow the low water level. In Fig. 3 the links are substantially vertical, the intake pipes 37 being in their uppermost positions corresponding with high water level. As the levels change the nicely balanced float structure readily responds and the intake pipes 37 accurately follow the water.

In Fig. 4 the details of construction of a float unit are shown. I preferably make the float of two cup-shaped halves 61 and 62 by stamping and drawing from sheet steel, the inner edges of these halves having the flanges 63 and 64 between which I insert a steel disk or diaphragm 65. The flanges and disk may be apertured to receive rivets 66 and preferably the flanges and disk are welded together to form an air-tight joint.

The end of one cup has a valve thimble 67 inserted therein for receiving the threaded valve 68 adapted for connection with an air pump in order that compressed air may be charged into the float, the diaphragm having the hole or passageway 69. A unit as constructed above possesses great strength and will not collapse under the heavy pressures found in boilers. In order to protect the steel float I preferably electro-plate it with copper and then burnish the copper deposit with a piece of hard steel in order to close the pores to prevent moisture from penetrating and reaching the steel shell.

I thus provide a simple and inexpensive boiler skimming apparatus constructed of ordinary metal piping, fittings, and simple connecting couplings together with floats of simple and inexpensive construction. Owing to the arrangement of the float units, the frictionless couplings, and the counter-balance arrangement, the apparatus quickly responds to and follows the changing levels. To facilitate installation of the apparatus a union 70 may be inserted in the longitudinal piping 10. By means of this union and the disconnectible heads of the piping couplings, the piping can be readily taken apart for installation and reconnected inside the boiler.

I do not, of course, desire to be limited to the exact construction and arrangement shown and described as modifications are no doubt possible which would still come within the scope of the invention. I claim the following:

The combination with a boiler having a supporting pipe extending therethrough, of skimming apparatus, a supporting frame for said skimming apparatus comprising longitudinal piping and transverse piping at the ends thereof, said piping being interconnected and having a valve controlled outlet, said piping resting on said boiler pipe, straps extending from said transverse piping around said boiler pipe to hold said supporting frame in place, parallel piping arms at each side of said supporting frame coupled to the respective ends of the transverse piping, an intake pipe at each side of said supporting frame coupled to the ends of the respective arms, said intake pipes having inlet openings for scum, foam or other impurities, and float members adjustably secured to said intake pipes.

In witness whereof I hereunto subscribe my name this 8th day of May, A. D., 1916.

WILLIAM J. BAUER.
